UNITED STATES PATENT OFFICE.

THOMAS C. WHITE, OF ST. LOUIS, MISSOURI.

DESIGN FOR AN INSULATOR.

44,118.

Specification for Design.

Patented May 27, 1913.

Application filed March 17, 1913. Serial No. 755,040. Term of patent 7 years.

To all whom it may concern:

Be it known that I, THOMAS C. WHITE, a citizen of the United States, residing in the city of St. Louis and State of Missouri, have invented a new, original, and ornamental Design for Insulators, of which the following is a specification, reference being had to the accompanying drawing, forming a part thereof.

In the drawing, Figure 1 is a plan view of an insulator showing my new and ornamental design. Fig. 2 is a side elevation

and Fig. 3 is an elevation at right angles to that shown in Fig. 2.

I claim:

The ornamental design for an insulator, as shown.

In witness whereof, I have signed this specification at the city of St. Louis and State of Missouri.

THOMAS C. WHITE.

In the presence of—

L. C. KINGSLAND,
BERNIE M. WATSON.
